AIRCRAFT POSITIONING VEHICLE

Ralph E. Walsh, Long Branch, N.J.

Application September 26, 1958, Serial No. 52,776

Term of patent 14 years

(Cl. D14—3)

FIG. 1

FIG. 2

FIG. 3

FIG. 4

Figure 1 is a top plan view of an aircraft positioning vehicle showing my new design.

Figure 2 is a side view of the vehicle shown in Figure 1.

Figure 3 is a view in front elevation of the vehicle shown in Figure 1.

Figure 4 is a view in rear elevation of the vehicle shown in Figure 1.

I claim:

The ornamental design for an aircraft positioning vehicle, substantially as shown.
